UNITED STATES PATENT OFFICE.

HERMAN BORCHERS AND ELI M. CHAMNESS, OF INDIANAPOLIS, INDIANA.

MEAT-TENDERER.

SPECIFICATION forming part of Letters Patent No. 354,679, dated December 21, 1886.

Application filed October 12, 1886. Serial No. 216,038. (No model.)

To all whom it may concern:

Be it known that we, HERMAN BORCHERS and ELI M. CHAMNESS, of Indianapolis, in the county of Marion and State of Indiana, have 5 invented certain new and useful Improvements in Meat-Tenderers; and we do hereby declare that the following is a full, clear, and exact description thereof, reference being had to the accompanying drawings, and to the letters of reference marked thereon, which form 10 part of this specification, in which—

Figure 1 represents a perspective view of the device complete. Fig. 2 is a vertical cross-section of the same, showing the manner of 15 securing the parts together; and Fig. 3 is a transverse vertical section on line $x-x$, Fig. 2.

This invention relates to improvements in meat tenderers and cutters, and has especial reference to the manner of securing the points 20 of the tenderer to the body of the device.

The invention consists in the novel construction and arrangement of parts hereinafter described, and particularly pointed out in the claim.

25 Referring by letter to the accompanying drawings, A and B designate the two main parts of the tenderer, secured together as hereinafter described.

The part A is in general form like a hatchet, 30 only having an enlarged head, a , as shown, and made preferably square or of other suitable contour. The part A is provided centrally with an eye or opening, a' , for the insertion of a handle, and its upper edge is 35 formed into a cutting-blade or chopper, a'' , which may be used to separate the meat into suitable-sized pieces for cooking, or to cut or break bone or gristle.

The part B is formed of a series of metallic 40 toothed strips, b' , and cast-metal body b . The body b has a flat upper surface adapted to fit against the surface of the head a , with which it corresponds in shape. The strips b' are 45 preferably of steel, serrated on one edge to form the teeth b'' , which resemble those of an ordinary saw, although other forms of teeth may be used, if desired.

The strips are nearly equal in length to the 50 width of the body b , and are secured thereto as follows: The mold-flask being properly prepared for casting the body or plate b , the strips b' are placed in the mold teeth downward, and forced down until the teeth are below the bottom of the mold and protected by

the sand. The heated metal, when poured into 55 the mold, will inclose the upper portion of the strips b' , while the teeth b'' will stand out from the lower surface thereof. The strips b' thus form substantially an integral portion of the body b . If desired, the upper edges of the 60 strips may be roughened to give them a firmer hold in the body b ; but this will seldom be necessary unless the tenderers are made unusually large.

The part B, completed as described, is secured to the head a of part A by means of rivets C, which pass through corresponding perforations, $c c$, in the body b and head a . 65

If desired, the part B may be secured to part 70 A by means of screws instead of rivets, so that the parts A and B may be separated to permit the head a to be used for pulverizing spices or other condiments. The manner of using this invention is obvious from the foregoing description.

75 By making the tenderer of two parts, A and B, as described, either part can be replaced when broken, and the expense of manufacturing them much reduced.

We are aware that meat-tenderers have been 80 made having their heads cast with a series of integral pyramidal projections or teeth; and we are also aware that it is not new to cast the metal of the tenderer-head around a number of rows of separate teeth or cutters, and we 85 therefore do not make a claim to such constructions, broadly; but,

Having described our invention, what we 90 claim is—

As an improved article of manufacture, a 95 meat-tenderer consisting of the part A, having a cutting-blade, a'' , eye a' , for the reception of the handle, and enlarged flat head a , and the part B, consisting of the metal body b , cast with the serrated steel blades b' , extending unbrokenly across its outer surface, the serrations of the blades forming the teeth of the tenderer, the body b being secured to the head a by rivets, substantially as described.

In testimony that we claim the foregoing as 100 our own we affix our signatures in presence of two witnesses.

HERMAN BORCHERS.
ELI M. CHAMNESS.
